AIRCRAFT PASSING AND LANDING LAMP

Charles L. Munroe, France Field, C. Z., and James H. Herr and Arnold D. Dircksen, Dayton, Ohio

Application September 26, 1940, Serial No. 358,468

2 Claims. (Cl. 240—41.35)

(Granted under the act of March 3, 1883, as amended April 30, 1928; 370 O. G. 757)

The invention described herein may be manufactured and used by or for the Government for governmental purposes, without the payment to us of any royalty thereon.

The present invention relates generally to lamps and more particularly to a lamp incorporating with a main light, an auxiliary light such as, in an automobile headlight incorporating a parking light, or in an airplane landing light incorporating a running or passing light.

It has been a common expedient in the electric lamp art to promote lamp efficiency by using a polished reflecting hood over the forward part of the light bulb to prevent direct rays of the bulb from passing out of the lamp. Such a lamp has what may be termed a dead spot or zone of substantially no light ahead of the reflecting hood. This zone can therefore be utilized with advantage by placing therein an auxiliary lamp, since if it were not embodied here it would necessitate a separate structure or assembly and would have to be mounted elsewhere.

Our invention contemplates the employment with such a lamp of an auxiliary light ahead of the main light in the blind area, and a double or two-way reflector disposed between the two lights, to thereby utilize this heretofore useless area for the auxiliary light without impairing the efficiency of either light source.

A further object of our invention is the mounting of both the two-way reflector and the auxiliary light source upon one support having means within the support for rotating the reflectors and auxiliary light outwardly and away from the main light to provide ready access to the main light for replacement thereof.

These and other objects will become more apparent as we proceed with the description and drawing, in which like numbers refer to corresponding parts and wherein:

Figure 1 is a section view with parts in elevation showing a lamp incorporating our invention.

Figure 2 is an enlarged view in perspective, of the support for the auxiliary light and two-way reflector.

In the drawing, the lamp assembly is composed of a housing 10 substantially semi-circular in cross-sectional conformation and having on the outside of the large or open end, a lens-securing means 11, comprising an external ring 12 having formed therein suitable attaching means, such as threads or the like, for holding the ring 12 fixedly to the housing 10. The ring 12 has formed integral therewith an inwardly projecting shoul-

der 13. This shoulder is utilized to hold the lens 14 in place. The housing 10 at its open end is folded inwardly to form a radius, as at 15, and a rearwardly projecting flange 16. The radius 15 forms a backing support against which the lens 14 is held by the ring 12. Interposed between the ring and lens is usual backing material.

The rearwardly projecting flange 16 forms a bearing surface for holding in place the front or open end of a parabolic reflector 17. The base or rear of the hemispherical housing 10 has a rearwardly projecting hollow cylindrical extension 18 integral therewith. Within the extension 18 is a similar integral extension 19 of the parabolic reflector, and of such a size as to telescopically form a tight or pressed fit within the extension 18. The hollow cylindrical projection 19 is interiorly threaded for receiving the main light bulb 21. The extension 18 of the housing is externally threaded to receive a contact-retaining cap 22, the said cap holding therein any suitable form of contactor (not shown) in fixed relation so as to cause a flow of electrical energy from the lead wires 23 into the bulb 21. As illustrated, a mounting bracket 38 is attached to the housing 10 by rivets.

As will be seen in the drawing, the main bulb 21 is positioned upon the longitudinal axis of the lamp and also at the focal point F of the parabolic reflector 17. Immediately ahead of the lamp 21 and symmetrical with the longitudinal axis is a two-way or double concave reflector 24, preferably of a diameter corresponding to the diameter of the main bulb. However, it will be understood that the size of the reflector 24 will vary with the distance it is spaced from the main bulb, so as to extend between the lines 39 and 40 connecting the outer edge of the main reflector 17 to the focal point F. The inner side 25 of the reflector is preferably spherically shaped to reflect the undesirable forwardly emitting rays from the main bulb 21 back to the filament or light source. This action results in the formation of greater heat intensity at the filament and consequently greater light intensity of the main light source. The reflector 24 also acts as a shield intercepting all the direct rays of light from the main source 21 which fall between the lines 39 and 40. There is thus produced a zone forward of the reflector 24 which receives no direct illumination from light 21. It will be understood that this same zone will be formed whether the surface 25 is made to function as a reflector or merely a shield.

The outer side 26 of the double concave re-

ALUMINUM BRONZE CONTAINING
COMPOSITIONS

Dean Murphy, Rahway, N. J., assignor, by mesne assignments, to Chadeloid Chemical Company, a corporation of West Virginia

No Drawing. Application October 11, 1938,
Serial No. 234,489

8 Claims. (Cl. 260—29)

This invention relates to aluminum bronze containing compositions, and particularly to such compositions enabling decorative effects to be secured.

In the prior art, aluminum bronze compositions have been used, but brilliancy of effect and stability of composition has not been secured.

Among the objects of the present invention is the production of aluminum bronze containing compositions which exhibit high brilliancy.

Other objects of the invention include the production of aluminum bronze containing compositions of decorative character and relatively high stability.

Still further objects and advantages of the present invention will appear from the more detailed description set forth below, it being understood, however, that this more detailed description is given by way of illustration and explanation only and not by way of limitation, since various changes therein may be made by those skilled in the art without departing from the scope and spirit of the present invention.

This application is a continuation in part of application Serial No. 553,007, filed July 24, 1931, entitled "Opalescent lacquers."

In accordance with the present invention, aluminum bronze containing compositions are produced by the utilization of various expedients. In the first place, in order to secure the best brilliancy in the composition, the aluminum bronze is desirably employed in paste form in admixture with petroleum spirits or other similar petroleum distillates or vehicles of related hydrocarbon character. By incorporating aluminum bronze with such vehicle using proportions to give a paste material, an aluminum bronze composition is produced having pronounced brilliancy enabling it to be desirably employed either in and of itself for various purposes, or for admixture with various vehicles, such as lacquers, cellulose ester type or resin type, etc., as more particularly illustrated below, and particularly to such compositions when pigmented.

The aluminum bronze may, however, be incorporated into various compositions without necessarily utilizing the bronze in paste form as indicated above, although the use of the paste form of aluminum bronze gives preferred results. Thus the aluminum bronze may be suspended in a desirable coating composition containing film-forming ingredients, such as cellulose derivatives, including nitrocellulose, cellulose acetate, cellulose ether, resins, etc., the color effects desired in

the final coating being secured by the incorporation of various colors into the composition, the color preferably being added to the coating composition containing the film-forming ingredient, 5 prior to incorporation of the aluminum bronze therewith. Thus aluminum bronze is incorporated with a colored or dyed lacquer solution. Since the aluminum does not liver, and is relatively stable towards any of the organic acids and even traces of sulphur that are sometimes present in these various lacquer vehicles, no deleterious effects are obtained and no livering occurs such as takes place with the copper bronzes and similar materials.

15 The coloring agents employed may be of two types—either the soluble or the insoluble colors, the first or soluble colors being generally hereinafter referred to as dyes, and the second class or insoluble colors being hereinafter referred to as pigments.

20 Of the dyes, the water-soluble aniline colors are preferred, since they are relatively stable to light, and do not result in any substantial amount of bleeding when topcoats or overcoats are applied over the coatings referred to. In view of the stability of the water-soluble aniline colors for the reasons discussed above, they are preferred to the other types of aniline dyes or other dyes including the oil-soluble and spirit-soluble 25 aniline colors, while the less stable dyes such as oil soluble and spirit soluble colors may be used, the stable water soluble colors are far more desirable. As exemplary of the water-soluble aniline colors that are particularly desirable for use 30 in this connection, the following may be mentioned Buffalo black, NBR, conc. and No. 4523 Nigro black conc.; Azo Rubine ex. conc. and amacid brilliant crocine 3BA conc.; orange A conc.; fast wool yellow 3 GL; Resorcine brown; 35 and alkali green 2 GO. Such water-soluble aniline colors may be incorporated with the usual lacquer compositions, the solvent vehicles employed being such as to give solution of the several ingredients. Any of the ordinary nitrocellulose lacquers may be employed for this purpose 40 and the desired dyes may be dissolved directly in the lacquer compositions containing the necessary solvent vehicles, or the aniline dyes may first be dissolved in various solvents, and then added 45 to the nitrocellulose lacquer composition. The nitrocellulose lacquer composition illustrates one type of film-forming coating compositions that may be employed in this connection. Desirably the lacquer compositions may contain glycol 50 ethers as one of the solvent elements in order to

55

maintain satisfactory solutions of the water-soluble aniline dyes, particularly the blacks, such as the nigrosines. For example, these aniline dyes may be dissolved in a vehicle containing 1 part "Carbitol," 9 parts methyl alcohol, and 6 parts toluol, 2 to 2½ ounces of the particular dye being used to one gallon of the composite solvent, and this may then be incorporated with the desired nitrocellulose lacquer composition. The amount of dye solution added to the lacquer composition will be determined by the depth of color desired therein. The dyed lacquer compositions prepared in this way may then be incorporated with aluminum bronze in any desired manner to give the final dyed lacquer aluminum composition utilizable as a coating composition. Desirably the lacquer compositions will also include resins in accordance with the best lacquer developments now recognized in the art. And when these compositions are to be employed for exterior exposure, it is desirable to include some of the "rezyls," that is the phthalic glyceride types of resins which contain fatty oils or fatty oil acids, and particularly the acids derived from drying oils, combined in these resin molecules. The presence of the "rezyls" in the compositions gives the compositions the desirable property of satisfactory durability on exterior exposure.

While very desirable opalescent and colored bronze effects may be obtained by the use of water-soluble aniline dyes as stated above, which yield compositions that do not fade or bleed, improved results are obtained by the use of insoluble pigments as the coloring medium. Of the insoluble pigments, those which are translucent, such as the lake colors are preferred. When opaque or substantially opaque pigments are employed, the amount of the opaque pigment used in the composition should be such that the coating deposited from the composition does not give a solid ground color, since in this way coatings having diaphanous or light-transmitting properties essential in carrying out the present invention, are obtained. Among the lake and other colors that are particularly desirable in carrying out the present invention, there may be mentioned the natural and synthetic lake colors including cochineal, madder, illustrating the natural lake colors, and any of the synthetic lakes which are usually prepared from the aniline colors deposited on aluminum hydrate or any other similar bulky translucent base, while in addition other pigments that may be employed include Prussian blue, Van Dyke brown, umber, etc. Of these, the lake colors, Prussian blue and Van Dyke brown are preferable instances of the insoluble pigments employed in accordance with the present invention. Any of these pigments may be ground in a suitable vehicle, and subsequently incorporated with the film-forming compositions, such as nitrocellulose lacquer.

Of the synthetic lake colors, preferably those are employed which are made by the use of water-soluble aniline dyes, since such water-soluble aniline dyes are light fast, and are therefore preferred to the oil-soluble and spirit-soluble anilines.

The effects obtained by the use of the insoluble pigments as opposed to the dye compositions set forth above are preferred because deeper effects are obtained with the pigment-containing compositions. However, both types of compositions yield satisfactory opalescent lacquers and colored bronze effects, the color, of course, depending on the nature of the dye, pigment or other

color employed in the composition, so that bronze, copper, gold effects may be readily obtained with these compositions. In general, these pigmenting materials discussed above may be 5 classified as including the synthetic lakes, and particularly those prepared by the use of water-soluble aniline dyes, the translucent vegetable colors, such as madder, translucent insect or animal pigments, such as cochineal, and inorganic 10 pigments, such as Prussian blue and burnt umber.

In incorporating the aluminum bronze with the film-forming composition, any desirable method may be employed, but it has been found that improved results are obtained if the aluminum bronze is first dispersed in paste form in some vehicle, such as petroleum spirits, or other medium compatible with the other components that are to be employed in the composition. The 15 aluminum bronze in paste form is more brilliant than the dry aluminum bronze of the same fineness. The aluminum bronze in dispersed form, such as a paste produced in this way, may then be directly incorporated by any desired mixing operation with the lacquer or other film-forming composition, and thorough dispersion is thus 20 readily obtained without the necessity of elaborate mixing or grinding that might otherwise be necessary. By using such aluminum paste material, the final coating compositions are also 25 improved in character, since they yield a very even laying on of the powder on the surface, and a remarkably complete coverage being secured with but a few ounces of the aluminum bronze 30 under these circumstances, whereas without such a vehicle, a much larger amount of bronze is 35 generally required. In securing the opalescent finishes, relatively small amounts of aluminum bronze may be employed in the compositions 40 and up to a certain point, increase in the amount of the aluminum bronze increases the opalescent effect. Beyond that point, increase in the 45 amount of aluminum bronze will to some extent decrease the opalescent effect and give a substantially solid ground color, but even in those cases 50 where a higher content of aluminum bronze is employed than is normally necessary for the opalescent finish, the introduction of the aluminum bronze in the dispersed condition in the hydro- 55 carbon or other vehicle still yields a substantially smooth finish, free from rough irregularities such as those exhibited by the copper base bronzes. By variation in the relative amount of coloring matter to aluminum bronze, variation in shade of color is secured, deeper shades being obtained with more coloring matter and less aluminum bronze, whereas more bronze and less color gives lighter shades.

The vehicle employed should also be of such 60 character as to avoid any substantial floating effect of the aluminum bronze, particularly when sprayed. In some instances, there may be a slight float when the composition is brushed on to the desired surface. Many of the vehicles 65 on the market employed for similar purposes may be utilized in the present types of compositions. Almost any vehicle that sets practically 70 instantaneously to an amalgam can be employed in accordance with the present invention. That is, if such vehicles remain rather plastic or oily for a short time, floating will result. In general, the composition should be such that there is a rapid expulsion of the solvents in order to get proper set, and under such circumstances no 75 floating effect will result. When resin solutions
